UNITED STATES PATENT OFFICE.

MORTIMER C. BAILEY, OF DERBY, CONNECTICUT, ASSIGNOR OF ONE-HALF TO EDWARD H. HANCOCK, OF SHELTON, CONNECTICUT.

COIN-SELECTING MECHANISM FOR COIN-OPERATED VENDING-MACHINES.

1,060,307.

Specification of Letters Patent. Patented Apr. 29, 1913.

Application filed October 11, 1912. Serial No. 725,152.

To all whom it may concern:

Be it known that I, MORTIMER C. BAILEY, a citizen of the United States, residing at Derby, in the county of New Haven and State of Connecticut, have invented a new and useful Improvement in Coin-Selecting Mechanism for Coin-Operated Vending-Machines; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a coin-selecting mechanism constructed in accordance with my invention, a portion of one side of its case being broken away, as well as a portion of one of its movement-plates. Fig. 2 a corresponding view taken from the opposite side of the case but without breaking the other movement-plate away. Fig. 3 a view of the mechanism in transverse section on the line *a—b* of Fig. 2. Fig. 4 a broken view of the mechanism in vertical section on the line *c—d* of Fig. 1, looking rearward in the direction of the arrows *A*, and drawn to twice the scale of the preceding figures.

My invention relates to an improved coin-selecting mechanism for use in conjunction with coin-operated vending machines, the object being to provide simple, reliable and efficient means for guarding against the sur-reptitious operation of coin-operated vending machines by the introduction of blanks or slugs into them in lieu of true coins.

With these ends in view, my invention consists in a coin-selecting mechanism having certain details of construction and combinations of parts as will be hereinafter described and pointed out in the claims.

In carrying out my invention as herein shown, my improved mechanism is organized as a separate unit adapted to be combined with any suitable coin-operated vending machine, the only requirement being that my improved device shall be placed so as to receive the coin before the coin passes into the vending machine. If preferred, however, my improved mechanism may be organized with the coin-operated vending machine it is designed to guard, but in

either case, its construction and principle of operation will be substantially un- 55 changed.

As herein shown, I employ an escutcheon-like gage 2 having a narrow coin-slot 3 closely gaged in size to the size of the coin which it is designed shall operate the vending machine which is not shown, but which, as aforesaid, may be of any approved character and construction, and for any purpose for which such machines are made. The said gage 2 is mounted in the top 4 of a 60 case which also comprises sides 5 and 6, a front end 7, a rear end 8, and a bottom 9. The case may, of course, be changed in form, and, if preferred, the gage 2 may be located on one side of it rather than on 65 top of it.

As shown, the coin-slot 3 opens directly into the upper end of a main coin-passage 10 having a straight upper arm, a rearwardly debouching curved lower arm, and 70 what I shall call a selecting-chamber 11 located at the point where the said arms merge into each other. A shunt coin-passage 12 leads forward from the lower end 75 of the upper arm of the said main coin-passage 10 and opens downward into a slug-chamber 13 located in the forward lower corner of the case inclosing the mechanism. The said coin-passages 10 and 12 are formed 80 in a filler-plate 49 substantially conforming to the thickness of the coins designed to be used and interposed between two fixed 85 vertically arranged movement-plates 14 and 15 located in the center of the case.

A primary deflector 16 forming a part of 90 the filler-plate 49 is located in the lower portion of the straight upper arm of the main coin-passage 10 just forward of the vertical center thereof, and therefore in position to normally deflect all coins and 95 slugs from front to rear into the selecting-chamber 11, as clearly shown in Fig. 1, whereby all coins and slugs will be directed into the said selecting-chamber 11 in which they will be brought to rest upon a manually operable horizontally arranged stoppin 17, as shown by the coin 18 in Fig. 1. In case a second coin or slug is introduced 100 into my improved coin-selecting mechanism before the coin or slug last introduced into 105 the mechanism has been selected or rejected,

and while it is still resting upon the said stop-pin 17, the second coin or slug will collide with the upper edge of its immediate predecessor and be deflected forward 5 by gravity over the high point of the primary deflector 16 and into the coin-shunt passage 12 from which it will drop into the slug-chamber 13.

In Fig. 1 I have shown a coin 18 as resting 10 upon the pin 17, and a slug 19 as being deflected by the said coin 18 into the coin-shunt passage 12. It will be observed that the distinction between the coin 18 and the slug 19 is that the former is furnished with an over- 15 hanging rim, while the sides of the latter are flat.

From the passage 12, the superfluous coin or slug, as the case may be, drops upon an inclined deflector 20 extending from front 20 to rear in the slug-chamber 13 and operating to deflect the coin or slug upon the forwardly curved bottom 21 of the said chamber, whereby the coin or slug will be deflected from the vertical to the horizontal 25 plane and caused to slide forward and emerge through the horizontal discharge-slot 22 at the lower extremity of the front end 7 of the case and then appear in the trough-like coin-receptacle 23. It will thus 30 be seen that if any one attempts to pervert the operation of my improved selecting-mechanism by introducing a second coin or slug into it without disposing of the last preceding coin or slug introduced into it, the 35 second coin or slug will, so to speak, be shunted through the mechanism, and almost immediately reappear in the receptacle 23; but no coin or slug will pass through the shunt-passage 12 unless at the time of its in- 40 troduction into the mechanism there happens to be a coin or slug supported upon the stop-pin 17. In that case, the supported coin or slug acts as a deflector for any subsequently introduced coins or slugs until the coin or 45 slug supported by the stop-pin 17 has been selected or rejected in the chamber 11 as will be described later on.

Any coin or slug introduced into the machine so as to assume the position of the 50 coin 18 in Fig. 1, operates to push outward and slightly retire from the upper portion of the selecting-chamber 11 a horizontally arranged yielding selecting-pin 24 mounted in the lower end of a vertical spring 25 se- 55 cured at its upper end by a screw 26 to the outer face of the movement-plate 14, as shown by broken lines in Fig. 1, the said plate 14 being provided with a transverse opening 27 receiving the pin 24 which is free 60 to move back and forth in it, as shown in Fig. 4. Normally the pointed inner end of the said pin 24 projects slightly into the selecting-chamber 11 as also shown in Fig. 4.

In line with the selecting-pin 24 is a corresponding selecting-pin 28 mounted hori-

zontally in the lower end of a spring 29 the upper end of which is fastened by a screw 30 to the outer face of the movement-plate 15 which is formed with a transverse opening 31 corresponding to the opening 27 afore- 70 said, and provided for the reciprocation in it of the pin 28, the pointed end of which is normally held just cleared from the selecting-chamber 11 by means of a horizontally arranged lever 32 resting upon a block 33 re- 75 ceiving a screw-stud 34 upon which the said lever 32 turns, and itself secured to the outer face of the movement-plate 15. The forward end of the said lever 32 co-acts with the inner face of a vertical operating-plate 35 secured to a block 36 fastened to the outer face of the lower end of the spring 29 carrying the pin 28, as shown in Fig. 3. The rear end of the said lever 32 co-acts with the upper end of a finger 37 extending upward 85 from the free rear end of the horizontally arranged operating-spring 38 which is fastened at its forward end by screws 39, 39, to the outer face of the movement-plate 15. The horizontally arranged stop-pin 17 afore- 90 said, is mounted in the said spring 38 and extends inward therefrom through an opening 40 in the movement-plate 15 into the middle of the selecting-chamber 11 at a point directly below the selecting-pins 24 and 28, 95 as shown in Figs. 1, 2 and 4.

For the operation of the spring 38, I employ a push-button 41 mounted in a bushing 42 in the side 5 of the case of the device, and held against being drawn outward in the 100 said bushing by means of a collar 43. At its inner end the push-button 41 passes through alined openings 44 and 45 in the plates 14 and 15 of the case, its projecting rear end being reduced in diameter as at 46 to enter 105 an eye 47 formed for its reception at the rear end of the spring 38, as shown in Fig. 2.

Below and a little in front of the stop-pin 17, I locate, as shown in Fig. 1, a secondary deflector 48 forming a part of the filler-plate 110 49 and over which the curved lower arm of the main coin-passage 10 debouches to the rearward.

It should now be explained that the operating-spring 38 is always superior in tension 115 to the spring 29 carrying the selecting-pin 28. Normally, therefore, the action of the spring 29 through its finger 28 and the lever 32, will be to overcome the tension of the spring 29, and hold the same in its sprung position in which it is shown in Fig. 4, and in which the selecting-pin 28 is withdrawn 120 from the chamber 11 into which the said pin is not allowed to move until the user of the device, by operating the push-button 41, overcomes the power of the spring 38 and allows the spring 29 to assert itself in projecting the selecting-pin 28 into the chamber 11.

Having now described the construction of 125

my improved coin-selecting mechanism, I will proceed to explain its operation.

The coin 18 when introduced into the coin-slot 3, will descend by gravity until it strikes the primary deflector 16, which will deflect it rearwardly into the selecting-chamber 11 in which it will be stopped and held by the stop-pin 17. Just before the said coin 18 comes in contact with the upper face of the stop-pin 17, the upper portion of its overhanging rim engages on one side with the selecting-pin 24 and crowds the same out of the said chamber 11. The coin having been lodged upon the pin 17 as described, and having been engaged with the selecting-pin 24, the user of the device begins to operate the push-button 41, whereby the operating-spring 38 is slightly sprung away from the outer face of the movement plate 15, thus moving its upwardly extending finger 37 away from the rear end of the lever 32 so that the tension of the spring 38 is removed from the said lever 32, and hence from the spring 29 which now asserts itself to move the selecting-pin 28 inward so as to engage with the overhanging rim on the opposite face of the coin which is now engaged by its rim on opposite sides thereof at a point directly above the stop-pin 17 which, meanwhile, has been backed out of the slot, but not sufficiently to remove its support from the coin. As soon, however, as both of the selecting-pins 24 and 28 have, in the manner described, been engaged with the opposite faces of the coin, the continued inward movement of the push-button will operate to entirely remove the stop-pin 17 from the selecting-chamber 11, and hence from the position in which it supports the coin, which will now be swung by gravity upon the selecting pins 24 and 28 as upon a center, until the center of the coin has passed the point of the secondary deflector 48. The movement of the push-button 41 being continued, its extreme inner end now engages with the lower end of the operating-plate 35, whereby the spring 29 is sprung outwardly sufficiently to disengage the selecting-pin 28 from the coin which then disengages itself from the pin 24 and drops downward through the curved lower end of the coin-passage 10 and functions the vending machine, whatever that may be. In swinging upon the pins 24 and 28 upon a center as described above, the coin sweeps through a vertically arranged coin-slot 50 leading from the selecting-chamber 11 into the slug-chamber 13, as shown in Figs. 1 and 2.

It will be readily understood from the foregoing, that if a dummy or slug 19 corresponding in gage to the coin 18 is introduced into the coin-slot 3, the operation of the mechanism will be as above described, except for the important difference that as the slug has no raised rim, instead of swing-

ing upon the selecting-pins 24 and 28 as upon a center when the stop-pin 17 is removed from under it, it will disengage itself from the said pins and drop with its center in front of the secondary deflector 48 by 70 which it will be deflected through the slot 50 into the slug-chamber 13 from which it will be ejected through the slot 22 into the slug-receptacle 23. In this way, the return, so to speak, of the slug to the person attempting to surreptitiously operate the mechanism, will indicate to him that he has failed of his purpose. The operation of the device will be the same with a smooth or much worn coin as with a dummy or slug, so that 80 by means of my improved coin-selecting mechanism, the public will soon learn that it can be operated only by legitimate and unworn or relatively perfect coins.

For the reason that the slot 50 aforesaid, 85 stands at a right angle to the slot 22, it is virtually impossible for anyone possessed of a great many slugs, to surreptitiously pass one through the mechanism in place of a legitimate coin by the introduction of a 90 great many slugs into the slug-chamber 13 through the slot 22. Slugs may indeed be introduced flatwise into the slug-chamber 13 through the horizontal slot 22, but the person who would work this "game" has no 95 means of controlling the slugs after their introduction into the slug-chamber, and hence cannot make them assume the vertical positions which they must take in order to move in reverse direction through the vertical 100 coin-slot 50 so as to enter the selecting-chamber 11 and so descend through the lower end of the coin-passage 10 into the vending machine the operation of which is the thing aimed at by this mode of attack. 105 As shown, the selecting-pins 24 and 28 are located directly over the stop-pin 17, but this is not essential, the only requisite being that they shall be positioned so as to cause the coin suspended from them to swing over 110 the high point of the secondary deflector 48 and enter the lower end of the main coin-passage 10.

It will, of course, be understood that my coin-selecting device may be adapted for 115 handling coins of any denomination, the size of the device and the tension of its spring being governed accordingly.

I claim:—

1. In a coin-selecting mechanism, the combination with two selecting-pins, arranged in line with each other and normally separated for the reception of a coin flatwise between them, and one of the pins being movable toward and away from the other 120 in line therewith, of a deflector located below the said selecting-pins upon which the coins turn as upon a center.

2. In a coin-selecting mechanism, the combination with two selecting-pins upon which 130

the coins are swung by their rims as upon a center, the said pins being arranged in line with each other and one being movable toward and away from the other in line therewith, of a deflector located below the said pins in position to co-act with coins and slugs according as they function in the said pins.

3. In a coin-selecting mechanism, the combination with two selecting-pins co-acting with the rims of the coins for swinging the same, the said pins being arranged in line with each other and one being movable toward and away from the other in line therewith, of a stop-pin located below the said selecting-pins for temporarily supporting the coins and slugs, and a deflector located below the said stop-pin to function the coins and slugs after they are released by the said selecting-pins and stop-pin.

4. In a coin-selecting mechanism, the combination with two selecting-pins co-acting with the rims of the coins for swinging the same, the said pins being arranged in line with each other and one being movable toward and away from the other in line therewith, of a stop-pin located below the said selecting-pins, a deflector located below the said stop-pin, and means connected with one of the selecting-pins and the said stop-pin for operating the same consecutively.

5. In a coin-selecting mechanism, the combination with two selecting-pins arranged in line with each other and one being movable toward and away from the other in line therewith, of a stop-pin located below the said selecting-pins and temporarily supporting the coins, and a push-button for the operation of the said stop-pin.

6. In a coin-selecting mechanism, the combination with two selecting-pins co-acting with the rims of the coins for swinging the same and so selecting the coins, the said pins being arranged in line with each other and one being movable toward and away from the other in line therewith, of a stop-pin located below the said pins, a push-button, and an operating-spring carrying the said stop-pin and operated by the said push-button.

7. In a coin-selecting mechanism, the combination with two selecting-pins, of a stop-pin located below the same and temporarily supporting the coins and slugs, a spring carrying one of the said selecting-pins, a push-button, an operating-spring carrying the said stop-pin and operated by said push-button, and connection between the said springs, whereby the selecting-pin specified is normally retired by the superior tension of the operating-spring, and brought into play by its carrying spring when the tension of the operating-spring is overcome by the operation of the push-button.

8. In a coin-selecting mechanism, the combination with a coin-passage having a straight upper end and a curved lower end, with a selecting-chamber located between the said ends of the passage, and selecting-pins located in the said selecting chamber and arranged in line with each other and one pin being movable toward and away from the other in line therewith.

9. In a coin-selecting mechanism, the combination with two selecting-pins arranged in line with each other, of two springs in which the said selecting-pins are respectively mounted and which permit their movement toward and away from each other in line with each other, a stop-pin located below said selecting-pins, a deflector located below the said stop-pin, and means for operating the stop-pin, the removal of which from under a coin or slug turns the same over to the action of the selecting-pins.

10. In a coin-selecting mechanism, the combination with a main coin-passage and a coin shunt-passage, of two selecting-pins located in the said main coin-passage and selecting the coins by their rims, arranged in line with each other and normally separated for the reception of a coin flatwise between them, and one of the pins being movable toward and away from the other in line therewith, a stop-pin located below the said pins, and a deflector, whereby coins or slugs introduced into the mechanism prior to the disposition by the stop-pin of the last preceding coin or slug to be introduced into the mechanism, are diverted into the said coin-shunt passage.

11. In a coin-selecting mechanism, the combination with a coin-passage containing a selecting-chamber, of a slug-chamber connected with the said selecting-chamber by means of a vertical slot, two selecting-pins arranged in line with each other and normally separated for the reception of a coin flatwise between them, and one of the pins being movable toward and away from the other in line therewith, and a stop-pin located below the said selecting-pins, by which the coins are arrested and upon which they are temporarily supported preparatory to the selecting action of the said selecting-pins, the slugs and coins not so selected passing through the said vertical slot into the said slug-chamber.

12. In a coin-selecting mechanism, the combination with a coin-passage containing a selecting-chamber, of a slug-chamber, a vertical coin-slot leading from the said selecting-chamber into the said slug-chamber, a coin-shunt passage leading from the upper end of the said coin-passage into the slug-chamber, selecting-pins located in the said selecting-chamber and arranged in line with each other and one of them being movable toward and away from the other in line

therewith, and a deflector located in the said slug-chamber for deflecting the coins entering it into a horizontal plane.

13. In a coin-selecting mechanism, the combination with a coin-passage, of a slug-chamber connected with the said passage by means of a vertical coin-slot, selecting-pins located in the said passage at a point therein adjacent to the said slot and arranged in line with each other and one being movable toward and away from the other in line therewith, and a deflector located below the said pins and deflecting the coins into the lower end of the said passage or into the said slug-chamber according to the functioning of the said pins upon the coins or slugs.

14. In a coin-selecting mechanism, the combination with a coin-passage, of a slug-chamber communicating therewith, coin-selecting pins located in the said passage, a

stop-pin located in the said passage below the said selecting-pins, springs carrying the said selecting-pins, an operating spring carrying the said stop-pin, connection between the said operating spring and one of the selecting-pin springs, whereby the pin carried by the said spring is normally re-tired, and a push-button co-acting with the said operating-spring, whereby the selecting-pin carried by the spring controlled by the operating-spring is permitted to engage with a coin before the stop-pin removes its support therefrom.

In testimony whereof, I have signed this specification in the presence of two subscribing witnesses.

MORTIMER C. BAILEY.
